MACHINE FOR SAMPLING COTTON

George E. Gaus, Washington, D. C., and Russell G. McWhirter, Stoneville, Miss., assignors to Henry A. Wallace, Secretary of Agriculture of the United States of America, and his successors in office

Application October 7, 1938, Serial No. 233,772

6 Claims. (Cl. 83—15)

(Granted under the act of March 3, 1883, as amended April 30, 1928; 370 O. G. 757)

This application is made under the act of March 3, 1883, as amended by the act of April 30, 1928, and the invention herein described and claimed, if patented, may be manufactured and used by or for the Government of the United States of America for governmental purposes without the payment to us of any royalty thereon.

This invention relates to a new and useful method of a machine for sampling cotton and it has for one of its objects the provision of a machine designed to remove a sample portion from a cotton bat after the bat is discharged from a cotton condenser and before it is baled.

Another object of this invention is the provision of a sampling device of the type mentioned, which is adapted to be operated intermittently for obtaining an average sample of each bale of cotton by rending sections from the cotton bat without disturbing the arrangement of the cotton fibers confined within the section so that the sections thus rended from the main portion when arranged in layers will be indicative of the quality of the ginned lint discharged from the cotton condenser.

The following description, considered together with the accompanying drawings, will fully disclose this invention, its constructions, arrangements, and combinations of parts and further objects and advantages thereof will be apparent.

In the drawings:

Figure 1 is a side elevational view of an embodiment of this invention partly in section; and

Figure 2 is a section along the line 2—2 of Figure 1.

Referring with more particularity to the drawings, in which like numerals designate like parts, the numeral 3 designates a horizontal platform supported on brackets 4 and 5, said platform having a central opening 6, preferably rectangular, and approximately the size of the sample desired to be obtained. The top surface of said platform 3 is provided with recesses or grooves 7, substantially as shown. Directly above said platform 3, a holding member 8, substantially identical in shape to the platform member 3, is disposed and has bordering ridges 9 on the bottom thereof complementary with the recesses 7. Vertical posts 10 are secured on the holding member 8. A vertical plate 11 is slidably mounted on said posts 10 and springs 12 are compressibly mounted on said posts 10 between the holding member 8 and the plate 11. Within the aperture of said holding member 8 a platen 13 is normally disposed and is secured to the bottom of vertical rods 14. Said rods 14 extend upward through

and are secured to the plate 11. Said rods also extend slidably through the bracket 15, terminating above said bracket and secured to a horizontal bar 17, substantially as shown. The bracket 15 is secured to a cross-bar 16 of the machine. 5 A lever 18 is pivoted by means of a stud pin 19 to a frame member 20 of the machine and it is connected to a link 21 by means of a slotted connection consisting of an arc-shape slot 22 in said lever 18, slidably engaging a pin 23 secured to 10 the upper end of said link 21. The lower end of said link 21 is pivoted to the bar member 17. A spring 24 is tensionally mounted between the ends of the opposite and shorter arm of the lever 18 and the frame member 20 beneath the pin 15 19. Another lever 25 is cofulcrumed with the lever 18 and carries a pin 26 slidably engaged with a slot 27 longitudinally disposed in the link 21. The other arm of said lever 25 is pivoted to one end of a short link 28, the other end of said 20 link having a slot 29 longitudinally disposed. A substantially Z-shaped lever 30, or any other suitable offset lever, is pivoted at its upper vertex below the pin 19, substantially as shown, on the frame member 20. The outer end of the upper 25 horizontal arm of said lever 30 is provided with a pin 31 which is slidably engaged in the slot 29. Near the pin 31, one end of a tension spring 32 is fixed, the other end of said spring being secured to the member 20. A platen 33 having a 30 centrally raised portion substantially congruent to the platen 13 is normally disposed beneath the platform 3, the central portion just fitting through the opening 6 so that it is flush with the top surface of said platform 4. Vertically slotted 35 guide links 34 are secured to the bottom of the side of the platform 3 nearest the frame member 20. Pins 35 attached to the platen 33 are slidably and pivotally disposed in the respective slots of said links 34. On the center of the bottom of the platen 33 a bracket 36 is secured and it is pivoted to one end of a link 37, the other end of said link being pivoted to the outer end of the lower arm of the lever 30. An adjustable abutment screw 38 is mounted on the member 45 20 to limit the return movement of the lever 30.

The operation of this invention is as follows: The lint cotton in continuous bat form is passed through the machine between the platform 3 and the holding member 8. At desired intervals the 50 lever 18 is pressed downward which has the effect of clamping the bat between said members 3 and 8. As the lever 18 is further pressed downward, the platen 13 exerts a force on that portion of the bat coextensive with the top portion of the 55

platens 33, at the same time forcing that portion of the bat, together with the platen 33, downward. This has the effect of tearing or rending this portion from the rest of the bat held between the members 3 and 8, the recesses 7 with their complementary ridges 9 preventing any slippage. When the platen 33 has been pushed down to the point where the pin 35 abuts the bottom of the slot in the link 34, the lever 25 is then pressed downward. This causes the platen 33 to pivot about the pin 35 into a vertical position permitting the sample obtained to fall. The purpose of the slot 29 is to maintain a definite play between the link 28 and the link 30, so that within the limits of this play, the spring 32 can exert an independent upward force against the bottom of the cotton bat which, together with the force being exerted on the top of said bat, a definite gripping action is obtained. If desired, this gripping action may be made more effective by providing ridges and complementary recesses in the platens 13 and 33, similar to those employed on the members 3 and 8, respectively. When the levers 18 and 25 are released, all parts of the machine return to their normal initial position by virtue of the action of the springs 12, 24 and 32. By repeating the action above described at different intervals of the cotton bat, the samples torn from the bat are deposited in layers, the one on top of the other, giving as a unit an average sample of the bale of cotton which is indicative of the quality of ginned lint discharged from the cotton condenser.

Having thus described our invention, we claim:

- 35 1. A cotton sampler machine comprising a horizontal support having an aperture therethrough, means for clamping the bordering edges of an area of cotton bat on said support, means independent of said first-mentioned means for clamping substantially the remaining portion of said area between platens, means for co-reciprocating in clamped relation said platens with respect to said support until the bat portion clamped between said platens is rended from said area.
- 40 2. A cotton sampler apparatus comprising a horizontal support having an aperture therethrough, means for clamping the bordering edges of an area of cotton in bat form on said support, a platen disposed beneath said support having a portion thereof substantially coextensive with said aperture, another platen disposed above said first-mentioned platen adapted to clamp the margins of a section of said bat area on said first-mentioned platen, said section being coextensive

5 with said aperture, means for co-reciprocating in clamped relation said platens vertically with respect to said support until the section of the bat therebetween is rended from said bat area, and means for revolving said first-mentioned platen to a substantially vertical position.

5 10 15 3. A machine of the character described comprising means for intermittently clamping the opposite sides of a portion of lint cotton in bat form, means for clamping the opposite sides of a section of said portion, means for rending said section in clamped relation from the remaining portion of the bat, and means for discharging the section so rended from the apparatus.

15 20 25 4. A cotton sampler machine comprising a horizontal support having an aperture therethrough, means for holding a portion of a bat of cotton on said support, means for clamping the opposite sides of a section of said bat portion substantially coextensive with said aperture, and means for tearing and separating said section in clamped relation from the remaining portion of the bat.

25 30 35 5. A cotton sampler machine comprising a horizontal support having an aperture therethrough, means for clamping the bordering edges of an area of cotton bat on said support, means independent of said first-mentioned means for clamping substantially the remaining portion of said area between platens, means for co-reciprocating in clamped relation said platens with respect to said support until the bat portion clamped between said platens is rended from said area, and means for discharging the portion so rended from the machine.

35 40 45 50 55 6. A cotton sampler apparatus comprising a horizontal support having an aperture therethrough, means for clamping the bordering edges of an area of cotton in bat form on said support, a platen disposed beneath said support having a portion thereof substantially coextensive with said aperture, another platen disposed above said first-mentioned platen adapted to clamp the margins of a section of said bat area on said first-mentioned platen, said section being coextensive with said aperture, means for co-reciprocating in clamped relation said platens vertically with respect to said support until the section of the bat therebetween is rended from said bat area, means for revolving said first-mentioned platen to a substantially vertical position, and means for discharging the rended section from the apparatus.
